SAFETY RAZOR

Filed Aug. 24, 1931

INVENTOR.
Walter P. Grath,

BY *R. W. Smith*
ATTORNEY.

UNITED STATES PATENT OFFICE

WALTER P. GRATH, OF LOS ANGELES, CALIFORNIA

SAFETY RAZOR

Application filed August 24, 1931. Serial No. 558,985.

This invention is a safety razor, and has for its object to provide for longitudinally adjusting the transverse cutting edge of a blade with relation to a guard, so as to vary 5 projection of the cutting edge in accordance with the requirements of the individual user. It is a further object of the invention to mount the blade in a holder which is longitudinally adjustable with relation to the 10 guard for varying longitudinal projection of the transverse cutting edge of the blade, with the blade readily removable and reinsertable without disturbing the longitudinal adjustment of its holder, so that with the holder 15 locked in adjusted position the transverse cutting edge of the blade will always have the desired longitudinal adjustment with relation to the guard.

It is a still further object of the invention 20 to provide for appreciable longitudinal adjustment of the blade holder with relation to the guard, so that blades of appreciably varying width may be mounted in the holder and the latter adjusted to provide the same 25 longitudinal projection of the transverse cutting edge of the blade with relation to the guard.

Further objects of the invention will be 30 readily understood from the following description of the accompanying drawing, in which:

Fig. 1 is a front elevation of the razor.

Fig. 2 is a rear elevation of the same.

Fig. 3 is a side elevation of the razor, partly in vertical section.

Fig. 4 is a bottom plan view of the razor with the handle detached.

The razor is of that type in which a blade 40 1 having a forward transverse cutting edge 2 is mounted upon a transverse support 3 having longitudinally projecting and transversely spaced guard teeth 4, the blade being shown in the present instance as a hollow-ground 45 blade terminating in a relatively heavy transverse rib 5 at its rear edge, and the support 3 being preferably provided with a boss 6 angularly disposed at its underside and detachably engaged by a usual depending handle 7 so as to incline the handle at the proper

angle with relation to the blade as shown in Fig. 3.

The transverse cutting edge of the blade is adapted for adjustment longitudinally of the guard teeth so as to adjust the cutting edge to 55 the requirements of the individual user; and when the desired adjustment has been obtained the blade may be removed and reinserted while maintaining the desired adjustment.

For this purpose the blade is mounted in a blade holder 8 which is slidably mounted on support 3 for adjustment longitudinally of guard teeth 4, the blade holder being recessed at its upper surface as shown at 9, 65 for reception of the blade with its cutting edge projecting appreciably forwardly beyond the holder and its ribbed rear edge impinging against a transverse abutment surface 10 at the rear of the recess. A spring 70 clip 11 is mounted on the holder so as to overlie the rear portion of the blade and frictionally hold it in place in recess 9; and the blade is thus readily removable and reinsertable by sliding it transversely along the 75 recess until clear of or engaged by the overlying spring clip.

The blade holder may be adjustably mounted on support 3 by providing the holder with transversely spaced guide ribs 12 80 at its underside, with the ribs slidably received in cooperating shouldered slots 13 which extend longitudinally of support 3 from its rear edge; and the blade holder may be locked in adjusted position by binding nuts 85 14 threaded onto pins 15 which depend from the ribs 12 through the slots 13.

The blade holder is adapted for accurate adjustment longitudinally of guard teeth 4 so as to provide any desired projection of the transverse cutting edge of the blade with relation to the guard; and for this purpose a bearing 16 may project rearwardly and downwardly from blade holder 8, with a screw 17 journaled in the bearing but fixed 90 against longitudinal displacement relative thereto, and threaded into a bore 18 which extends longitudinally through support 3. The screw may be rotated by a head 19, so that with binding nuts 14 loosened, turning the 100

head 19 provides positive and accurate adjustment of blade holder 8 in either of opposite directions longitudinally of teeth 4; and the blade holder may then be securely locked in adjusted position by tightening the binding nuts.

The blade 1 is thus held in adjusted position providing any desired projection of its transverse cutting edge 2 longitudinally of guard teeth 4, with the grinding nuts 14 forming a rigid structure of blade holder 8 and support 3 so that the blade maintains exactly the desired adjustment, and after using the razor the blade may be removed and cleaned and the handle 7 may also be removed, without disturbing the adjustment of holder 8, so that when the blade is again inserted in the holder it will have the same adjustment as previously determined in accordance with the requirements of the individual user.

When the blade has been ground away, the holder 8 is longitudinally adjusted to re-establish the desired longitudinal projection of the transverse cutting edge of the blade 25 with relation to the guard; and by making slots 13 of appreciable length the holder 8 may be adjusted so as to operatively position the blade even when it has been appreciably worn away as a result of repeated grinding.

A further advantage of this improved construction is the elimination of stops on the guard teeth 4 by supporting the blade entirely by the holder 8; and as a consequence the entire length of cutting edge 2 is without obstruction and thus adapted for use, with the ends of the cutting edge preferably rounded off as shown at 2^a so as to avoid the possibility of accidentally pricking the skin.

The invention thus provides an extremely simple and compact safety razor construction, adapted for convenient use and accurately adjustable to meet the exact requirements of the individual user.

I claim:

1. In a safety razor, a guard, a holder for a

blade mounted on the guard and adapted for adjustment for desired longitudinal projection of the transverse cutting edge of the blades with relation to the guard, a handle suspended from the guard, the guard having longitudinal slots laterally spaced at opposite sides of the handle, ribs on the blade holder slidably received in the slots, pins projecting from the ribs through the slots, and nuts threaded onto the pins for binding engagement against the guard so as to form a rigid structure of the blade holder and guard.

2. In a safety razor, a guard, a holder for a blade mounted on the guard and adapted for adjustment for desired longitudinal projection of the transverse cutting edge of the blade with relation to the guard, the guard and holder having a cooperating slot and projection, with the slot extending in the direction of longitudinal adjustment of the holder and the projection elongated in the same direction and snugly fitting the slot throughout the length of said elongated projection so as to guide longitudinal adjustment of the holder and prevent twisting thereof with relation to the guard, and means extending from the projection and cooperating with the wall of the slot for binding the longitudinally adjusted blade holder against the guard.

3. In a safety razor, a guard, a holder for a blade mounted on the guard and adapted for adjustment for desired longitudinal projection of the transverse cutting edge of the blade with relation to the guard, the guard having laterally spaced longitudinal slots, ribs on the blade holder slidably received in the slots, and means extending from the ribs through the slots for binding the longitudinally adjusted blade holder against the guard.

In testimony whereof I have affixed my signature.

WALTER P. GRATH.
